(57) **CLAIM**

The ornamental design for a combination power adapter and detachable battery, substantially as shown and described.

DESCRIPTION

FIG. 1 is a front, top perspective view of a combination power adapter and detachable battery showing my new design;

FIG. 2 is a front view thereof;

FIG. 3 is a back view thereof;

FIG. 4 is a left-hand side view thereof;

FIG. 5 is a right-hand side view thereof;

FIG. 6 is a top view thereof;

FIG. 7 is a bottom view thereof; and

FIG. 8 is another front, top perspective view thereof in an alternate configuration;

FIG. 9 is another front view thereof;

FIG. 10 is another back view thereof;

FIG. 11 is another left-hand side view thereof;

FIG. 12 is another right-hand side view thereof;

FIG. 13 is another top view thereof; and,

FIG. 14 is another bottom view thereof.

The broken line portions of the figure drawings are included to show unclaimed subject matter only and form no part of the claimed design.

1 Claim, 10 Drawing Sheets
